(57) **CLAIM**

The ornamental design for a head mounted display as shown and described.

DESCRIPTION

FIG. 1 is a right, top, front perspective view of a head mounted display in accordance with my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a left, top, rear perspective view thereof;

FIG. 9 is a sectional view taken along arrow 9-9 of FIG. 2, omitting internal mechanisms; and,

FIG. 10 is a sectional view taken along arrow 10-10 of FIG. 2, omitting internal mechanisms.

The broken lines shown in the figures depict portions of the head mounted display that form no part of the claimed design.
